UNITED STATES PATENT OFFICE.

THOMAS F. MORRIS, OF WATERFORD, NEW YORK.

SNAP-FASTENER.

1,352,374.

Specification of Letters Patent.

Patented Sept. 7, 1920.

Application filed April 17, 1920. Serial No. 374,704.

To all whom it may concern:

Be it known that I, THOMAS F. MORRIS, a citizen of the United States of America, residing at Waterford, in the county of 5 Saratoga and State of New York, have invented certain new and useful Improvements in Snap-Fasteners, of which the following is a specification.

This invention relates to an improvement 10 in snap fasteners, designed more particularly for use on gloves and the like, and wherein means are provided to prevent separation of the fastener member from the glove material under strain or stretching 15 of said material in use.

Snap fasteners of this type are applied in part through an opening formed in the material, and complementary parts of the fastener are forced, under clamping coöperation 20 of the fastener parts into contact with opposite surfaces of the fabric. Under the strain and stretching of the fabric with the fastener in use or in drawing on the glove, there is a tendency to stretch or 25 enlarge the opening through which the fastener is originally passed, and this frequently results in such an enlargement of the opening as to actually separate the fastener from the material.

The present invention is directed particularly to overcoming this tendency of opening enlargement under strain or stretching of the fabric, by providing an auxiliary securing means, integral with the 35 part of the fastener, and adapted in the clamping action necessary to fix the coöperating parts of the fastening elements to the fabric, to be so moved as to engage and hold the fabric about and beyond said opening, the securing means being so arranged 40 as to prevent any possibility of opening enlargement under any ordinary strains or stretching to which the fabric may be subjected.

45 In the drawings:—

Figure 1 is a vertical sectional view showing one type of the male member of a snap fastener, with the parts in coöperating relation prior to the setting pressure.

50 Fig. 2 is a similar view following the application of the clamping pressure, and showing the male member as finally secured in the fabric.

Fig. 3 is a vertical sectional view of a 55 complete fastener, with the improved securing means in both the male and female

members, the male being shown of a type somewhat different from that shown in Figs. 1 and 2.

Fig. 4 is a perspective view of the fastening member used in the form illustrated in Fig. 1.

Fig. 5 is a similar view of the fastening member used in the form shown in Fig. 3.

The improved snap fastener, includes as usual the male member 1 and female member 2, adapted to be secured to different fabric sections, to permit the connection or disconnection of such sections in the usual manner. The present invention is directed particularly to providing an auxiliary fastening means whereby the complementary parts of either the male or female member, act, when applied, to hold the fabric against the possibility of stretching to enlarge the opening through which the fastener part is applied.

In Figs. 1 and 2 there is shown the male member of a snap fastener, which aside from the particulars of the present improvement is of conventional type. As here shown this member comprises an annular disk-like element 3 having a hollow stud 4 projecting upwardly therefrom when adapted to be passed through an opening 5, formed in the fabric 6. The coöoperating or head member 7 has a head portion to encircle the upper projecting end of the stud 4, and a disk-like element 8 to overlie the upper surface of the fabric in opposition to the disk 3.

The characteristic detail of the present invention resides in providing one of the disks 3 or 8, as here shown the disk 3, with a series of spurs 9, preferably stamped from the disk and extending upwardly therefrom and inclined from the vertical toward the stud 4. These spurs 9 are preferably not of a length to extend materially through and beyond the fabric in the application of the parts, as will be particularly clear from Fig. 1 of the drawings. In fixing the element 7 to the element 3, the disk 3, or that disk having the spurs is arranged with the spurs in engagement with the surface of the fabric, the coöoperating parts are positioned, and a clamping pressure is applied to the disks 3 and 8, the upper end of the stud 4 being simultaneously enlarged within the head 7 and said head slightly bulged to provide the conventional snap head. Under this pressure the disks 3 and 8 will be

forced toward each other, compressing the fabric between said disks, and as the pressure continues, the free ends of said studs 9 are forced into the fabric and at the same time bent downwardly, thus bending the studs at a greater inclination to the vertical, until finally said studs are projected through or about to the upper surface of the fabric and present a sharp angle with relation to the upper surface of the disk 3, as will be seen in Fig. 2 of the drawings.

As heretofore constructed the fabric has been held between the complementary members of the snap fastener part merely by the clamping pressure of the disks 3 and 8, and under these conditions the stretching and strain of the fabric has gradually enlarged the hole 5, so that eventually the snap fastener part is substantially free from the fabric. With the present invention however it is to be noted that this hole enlargement is impossible, as any stretching or strain on the fabric tending to such hole enlargement, is immediately resisted by one or more of the studs 9, with the effect of maintaining the fabric between the disks 3 and 8 in substantially its original condition.

In the result gained by this construction it is to be noted that the fabric between the disks 3 and 8 is, through the compression thereof by the clamping pressure of the disks, substantially hardened or rendered more compact, and hence the effectiveness of the holding action of the studs 9 is materially increased. Furthermore it is to be noted that the studs 9 do not pass to any appreciable extent through and beyond the fabric and that when bent down by the clamping pressure they form no additional opening in the fabric beyond that formed in their original application. This causes the studs to more or less compress the fabric between them and the stud 4, which of course tends to increase the holding effect of the studs.

In Fig. 3 the invention is shown as applied to a slightly different, though well known type of head member of a snap fastener. In this figure the head proper 10 is provided with a disk 11 to overlie the upper portion of the fabric and has an integral stud 12 which passes through the opening 13 in the fabric. The member engaging the lower surface of the fabric is here shown as a washer-like element 14, adapted to encircle the projecting end of the stud 12. This element 14, which corresponds to the disk 3 in the form first described is provided with studs 15, which in applying the parts operate exactly as described in connection with the studs 9. In this form the clamping pressure is applied to the disks 11 and 14, and at the same time the projecting end of the stud 12 is upset beneath the washer 14 to hold the parts in clamped relation.

In Fig. 3, the invention is shown as ap-

plied to the socket member of the head fastener, to which of course it is as readily applicable as to the head member of such fastener. The socket member here shown, is of conventional form, and needs no description in detail other than indicating the studs 16, which may be secured to one or the other of the disks of such member between which the fabric 17 is clamped. These disks, when clamped cause an action of the studs 16 exactly similar to that described in connection with the studs 9 of Figs. 1 and 2.

It is of course apparent that the spurs 9 may, with equal facility and effect, be applied to either clamping disk, and while the particular disk employed for such spurs, is more convenient, any other application of such is contemplated.

Claims:

1. A snap fastener member including a part to pass through an opening in the material and also including disks adapted to be clamped on the material beyond said opening, and spurs projecting from one of said disks to be deflected toward the opening in the clamping of the disks.

2. A snap fastener member comprising disks between which the material is to be clamped by pressure on said disks, a stud carried by one of said disks to pass through an opening in the material, and spurs carried by one of said disks and normally inclined from the vertical toward said opening, said spurs being further deflected in the direction of their normal inclination as the clamping pressure is applied to the disks.

3. A snap fastener member comprising disks between which the material is held under a clamping pressure, and means carried by one of said disks to extend substantially through the material between the disks at an inclination to the plane and toward the center of the disks.

4. A snap fastener member including disks between which the material is to be held by clamping pressure, and spurs carried by one of said disks to extend substantially through the material between the disks and, at an inclination to the plane and toward the center of the disks.

5. A snap fastener member to be held in a hole in the material and including disks between which the material adjacent and surrounding said hole is clamped, and spurs carried by one of the disks to enter the material between the disks and extend substantially through the same at an inclination toward the center of the disk on which they are carried.

6. A snap fastener member comprising disks between which the material is compressed under a clamping action of the disks, and means carried by one of said disks and inclined toward the center thereof, said means being adapted to extend sub-

stantially through the compressed portion of said material and to be deflected by the clamping action to dispose the means at an inclination to the plane of the disks and in 5 a direction to resist displacement of the material between the disks.

7. A snap fastener comprising disks between which the material is adapted to be clamped, said disks encircling an opening in

said material, and spurs carried by one of 10 the disks and adapted under the clamping action of the disks to be inclined toward the opening to thereby hold the material about said opening against displacement relative to said disks.

15 In testimony whereof I affix my signature.

THOMAS F. MORRIS.
